UNITED STATES PATENT OFFICE.

HENRY LUKE, OF NEFFS, OHIO.

REFLECTOR ATTACHMENT FOR MINERS' LAMPS.

Application filed February 8, 1923. Serial No. 617,900.

To all whom it may concern:

Be it known that I, HENRY LUKE, a citizen of the United States, residing at Neffs, in the county of Belmont and State of Ohio, 5 have invented certain new and useful Improvements in Reflector Attachments for Miners' Lamps, of which the following is a specification.

My invention relates to improvements in 10 reflector attachments for miners' lamps, the primary object thereof residing in the provision of such a reflector, that may be expeditiously applied to all types of miners' lamps with which I am now familiar, the nature 15 of the same being such as to focus the light rays, and to project the same a considerably greater distance than is now the case with the conventional types of miners' lamps.

20 A further object of my invention is the provision of such an attachment that is comparatively simple of construction, and inexpensive of manufacture, the same being well adapted for ready attachment to and 25 removal from miners' lamps.

The nature and advantages of the invention will be better understood when the following detailed description is read in connection with the accompanying drawings, 30 the invention residing in the construction, combination, and arrangement of parts as claimed.

In the drawings forming part of this application, like numerals of reference indicate similar parts in the several views, and wherein:

Figure 1— is a fragmentary elevational view of a conventional form of miner's lamp showing my improved reflector associated 40 therewith.

Figure 2— is an elevational view of this lamp, together with my reflector thereon, the said reflector being shown in cross section.

Figure 3— is a top plan view of my reflector attachment per se, and

Figure 4— is a vertical transverse sectional view thereof.

Referring to the drawings in detail, and particularly to Figures 1 and 2, the miner's lamp includes the usual carbide receptacle 5, together with the water container 6, removably arranged thereon, which container is formed with an opening 7 at the front end of the lamp.

55 My attachment per se embodies a bowl

shaped metallic reflector 8 having an opening 9 therein. Formed upon the outer surface of this reflector is a curved plate 10, the said opening 9 within the reflector also passing centrally through said plate. The 60 top of the reflector is formed with an outlet tube 11 adjacent the open front end thereof, which tube has a protecting cap 12 removably arranged thereon.

The front opening of the reflector 8 is 65 formed to provide a channel 13 within which is arranged a bull's-eye lens 14, the said reflector inwardly of this lens being formed with annular rows of perforations 16. Within the said opening 7 of the water 70 receptacle 6 of the miner's lamp, there is brazed or otherwise secured one end of a tube or nipple 17, the opposite end being screw threaded externally as at 18, and adapted for detachably receiving an im- 75 proved form of burner tip 19. My reflector is adapted to be engaged over this tube 17, the curved plate 10 thereof having close contact with the adjacent surface of the water compartment 6 of the lamp for preventing 80 the rotation of the said reflector upon the lamp, the reflector being maintained upon said tube 17 by a nut 20 upon the screw threaded end 18 of said tube 17.

The reflector 8 is formed at one side with 85 a pocket 21 within which is maintained through the medium of a strap member 22 a small cylinder 23, which cylinder carries the usual stick of spark producing material. The upper end of this cylinder 23 extends 90 through an opening 24 in the upper end of said pocket and carries a friction wheel 25 a portion of which extends outwardly of the reflector through a slot 26 therein for permitting this friction wheel 25 to be rotated 95 for consequently producing sparks within the reflector for igniting the gas at the burner tip 19, it being readily understood that the perforations 16 within the reflector will permit of the entrance of air into the 100 reflector, while the outlet tube 11 will carry off the heat and gases.

In view of the above description, it is believed by me that the advantages of a reflector for miners' lamps of the character herein shown and described will be readily appreciated by those skilled in the art, and although I have set forth the preferred embodiment of my invention, it is nevertheless to be understood that minor changes may be 110

made therein, without departing from the spirit and scope of the invention as claimed.

What I claim as new is:

The combination with a miner's lamp having the water compartment formed with an opening and a sleeve member mounted in said opening and extended outwardly therefrom, and a burner mounted in the outer end of the sleeve, of a semi-spherical reflector having an opening formed in the central portion adapted to fit over the sleeve and engage the outer surface of the water compartment, a nut having screw threaded cooperation with said sleeve for securing said reflector to said compartment, means for positioning the reflector in a fixed rela-

tion with respect to said water compartment, the annular edge of said reflector being formed with a bead adapted to form a lens seat, a lens mounted in said seat, said reflector having a plurality of openings adjacent the beaded edge thereof extending entirely around said edge portion for reducing the heating of said lens, the upper portion of said reflector being formed with an upwardly extending tubular section having a removable cap positioned in substantial vertical alignment above said burner for providing effective ventilation of the heat therefrom.

In testimony whereof I affix my signature.

HENRY LUKE.
